(57) **CLAIM**

The ornamental design for a wireless controller charger, as shown and described.

DESCRIPTION

FIG. 1 is a right side view;

FIG. 2 is a front view;

FIG. 3 is a left side view;

FIG. 4 is a rear view;

FIG. 5 is a top view;

FIG. 6 is a bottom view; and,

FIG. 7 is a perspective view.

The broken lines in the drawings are for the purpose of illustrating portions of the wireless controller charger that form no part of the claimed design.
